UNITED STATES PATENT OFFICE.

KARL AXEL JAKOBSSON, OF STOCKHOLM, SWEDEN, ASSIGNOR TO WILLIAM FARRE,
OF CHRISTIANIA, NORWAY.

ACCORDION.

1,375,156.

Specification of Letters Patent. Patented Apr. 19, 1921.

Application filed October 7, 1919. Serial No. 329,036.

To all whom it may concern:

Be it known that I, KARL A. JAKOBSSON, citizen of Sweden, residing at Sundbyberg, Stockholm, Sweden, have invented certain 5 new and useful Improvements in Accordions, of which the following is a specification.

This invention relates to improvements in key-controlled wind instruments and more 10 particularly to accordions.

The object of the invention is to provide a simple inexpensive chord mechanism whereby a number of the air valves may be simultaneously operated.

15 With the foregoing object outlined and with other objects in view which will appear as the description proceeds, the invention consists in the novel features herein-after described in detail, illustrated in the 20 accompanying drawing and more particularly pointed out in the appended claim.

Referring to the drawing:

Figure 1 is a vertical sectional view illustrating my improved mechanism.

25 Fig. 2 is a plan view of the mechanism.

In the drawing 1, 2 and 3 designate the upper or chord keys of an accordion which are designed to control the air valves 4. Each of these air valves is rigidly connected 30 by a bent rod 5 to one of the rock shafts 7. The rock shafts are mounted in parallel relationship in the case 6 and each shaft is provided with an upwardly extending arm 8 which terminates in a vertical portion 9.

35 It will be noted that all of the extensions 9 lie in a single plane in order that they may be operated by the mechanism now described. Located between the keys 1, 2 and 3 and the extensions 9 are rods 10 provided

40 at their rear ends with angular extensions 11, the angular extensions of the uppermost rods 10 being of greater length than the angular extensions of the second and third rows and the angular extensions of the sec-

ond row being of greater length than the 45 angular extensions of the third row.

In the drawing the uppermost rods have their extensions 11 of sufficient length to engage and operate four of the extensions 9 so that depression of one of the uppermost 50 keys 1 will contemporaneously operate four of the valves 4.

The extensions 11 of the keys 2 are of a length sufficient to engage three only of the extensions 9 and in consequence depression 55 of one of the keys 2 will operate but three of the valves 4.

The extensions 11 of the keys 3 are of a length to operate two valves only.

From the foregoing it is believed that the 60 improved mechanism will be readily understood and it is apparent that the present construction will enable the valves and their operating mechanism to be readily reached for the purpose of repair or renewal. 65

What I claim and desire to secure by Letters-Patent is:

In an accordion, the combination with a plurality of air valves, of a series of parallel rock-shafts, rods connecting said rock-shafts 70 to the valves, an arm fixed to each rock-shaft and having an extension, the extensions of all of said arms lying in the same plane, an upper series of keys provided with rods having angular extensions designed to 75 simultaneously engage a plurality of the arm extensions, and other keys having rods provided with extensions of less length than the extensions of the first mentioned key-rods engaging a different number of the arm 80 extensions than the extensions of the first mentioned key-rods.

In testimony whereof I have affixed my signature in presence of two witnesses.

KARL AXEL JAKOBSSON.

Witnesses:

OTTO BRUNING,
E. LINDSEY.
